CLAIM

The ornamental design for a shoe, as shown and described.

DESCRIPTION

FIG. 1 is a side perspective view of a shoe.

FIG. 2 is another side perspective view of the shoe of FIG. 1.

FIG. 3 is a front view of the shoe of FIG. 1.

FIG. 4 is a rear view of the shoe of FIG. 1.

FIG. 5 is a side view of the shoe of FIG. 1.

FIG. 6 is another side view of the shoe of FIG. 1.

FIG. 7 is a top view of the shoe of FIG. 1; and,

FIG. 8 is a bottom view of the shoe of FIG. 1.

The evenly dashed broken lines show portions of the shoe that form no part of the claimed design. The dash-dot-dash broken lines define boundary lines that form no part of the claimed design.

1 Claim, 8 Drawing Sheets
